Harry C. Odenkirk
by Jas. L. Skidmore
his Atty.

UNITED STATES PATENT OFFICE.

HARRY C. ODENKIRK, OF CLEVELAND, OHIO.

SANITARY SELF-SEALING TRAP.

1,323,718.

Specification of Letters Patent. Patented Dec. 2, 1919.

Application filed July 8, 1919. Serial No. 309,495.

To all whom it may concern:

Be it known that I, HARRY C. ODENKIRK, citizen of the United States, residing at Cleveland, in the county of Cuyahoga and State of Ohio, have invented certain new and useful Improvements in Sanitary Self-Sealing Traps, of which the following is a specification.

My invention relates to a sanitary self-sealing trap especially designed for use in connection with bath tub waste drainage.

The prime object of this invention is to provide a simple, economical, durable and thoroughly efficient sanitary self-sealing trap, preferably of the drum type of construction, suitably connected to the waste pipe of a bath tub.

A further object of the invention is to so construct my improved trap as to dispense entirely with all movable parts and interior partitions, which in case of defect, would allow the passage of sewer air, and so that the water seal will protect the trap screw from sewer air.

Another object of the invention is to construct the trap from a single piece of cast metal having a threaded inlet at one side of the main body portion, and a threaded outlet at the opposite side of said body portion, said outlet being connected at the bottom portion of the body and extending upward at an angle of substantially 45° from the body, thus permitting it to be readily cleaned; both the inlet and outlet being so constructed that any of the well-known pipe threaded connections may be utilized in connecting with the trap, and the inlet and discharge outlet being on the same horizontal plane with respect to the body portion.

Another object of this invention is to so construct the trap that the mouth of the trap will be of the same size as its main body portion, and so that the trap will readily form its own seal without any partition, addition or removable parts connected therewith, excepting a screw-threaded removable cover secured to the top of the said body portion, which cover may be readily removed when it is desired to cleanse the trap.

The foregoing and such other objects as may occur from the ensuing description are attained by the construction, arrangement and location of the parts hereinafter more fully described, illustrated in the accompanying drawings and particularly pointed

out in the claims appended hereto, it being understood that slight changes in the form, proportions and minor details of the construction may be resorted to without departing from the spirit or sacrificing any of the advantages of the invention.

In the accompanying drawings which form a part of the specification, it will be seen that:

Fig. 1, is a view in side elevation showing the device embodying my invention in connection with a bath tub.

Fig. 2, is a perspective of my improved device showing it in disconnected position, and

Fig. 3, is a central sectional elevation of the device shown in Fig. 2.

Similar characters of reference are employed to designate corresponding parts throughout the several figures of the drawings.

In carrying out my invention as illustrated, it will be seen that the trap A is connected to the waste outlet of a bath tub B, by a threaded pipe connection 1, which is securely fitted to the threaded inlet 2, formed integral with the main body portion 3 of the trap, at one side thereof, and diametrically opposite to said inlet is formed the outlet or discharge member 4 of the trap, said outlet or discharge being integrally connected to the main body portion at the bottom of said body, and extending outward and upward at an angle of substantially forty-five degrees and terminating with a threaded portion 5 in the same horizontal plane with the inlet 2, said outlet being integrally connected with the body portion of the trap by an integral web or extension 6 forming a part of the trap, and constituting a strengthening and reinforcing portion thereof. Fitted to the threaded portion of the outlet is a threaded pipe connection 7, which leads to and is connected with the waste pipe 8, leading to a sewer.

It will be perceived that my improved trap is formed from a single piece of cast metal which may be coated with any suitable rust-proof coating, but is preferably formed from a single piece of galvanized cast-iron, and the top of the main body portion is screw-threaded and adapted to receive a screw-threaded nickel-plated removable metallic cover 9, provided with an annular portion extending beyond the

body portion, which may be readily removed to permit access to the interior of the trap for cleansing purposes, and it will be also obvious that owing to the discharge outlet being connected at the bottom of the body portion on a horizontal plane with said bottom and extending at an angle upward and outward therefrom, access may easily be had thereto from the interior of the trap by 5 a wire or other suitable means, for the purpose of cleansing or clearing said outlet, in the event it should become clogged or partly choked up from any cause whatever.

It will also be seen that the trap is self-sealing by the retention within the main body portion of a considerable volume of water which always remains therein between the inner end of the outlet portion and the lower end of the inlet portion, said volume 10 of water being sufficient to prolong the breaking of the seal by evaporation thereof, and always serving to prevent the escape of foul sewer gas or air into a room to which the fittings are connected and to protect the 15 trap screw and cover from contact therewith.

Owing to the precise construction of this trap, it will be readily obvious that since it dispenses with the action of movable parts, partitions, and additions for its seal, and 20 is provided with a large main body portion connected at its bottom with an outlet formed at an angle with respect to said body, that the trap is self-cleaning which materially lessens any liability of its discharge being clogged or otherwise interfered with.

While I have shown one mode of connecting my improved trap to a bath tub, it will be understood that any suitable or desirable 25 method may be employed in making the required connections.

Both the inlet and outlet are provided on their exterior surface with a series of integral ribs 30, adapted to receive a suitable 45 tool for holding the trap in a stationary position during the process of fitting the suitable pipe connections thereto.

From the foregoing description, it will be readily perceived that I have produced a 50 trap wherein the labor and expense of wiping joints in attaching the inlet and outlet pipes thereto is entirely dispensed with, a trap which is economical in production, which is self-sealing and self-cleaning, and 55 which will maintain and prolong an effective seal between the foul sewer gases which may accumulate in the waste pipes and the compartment in which the trap may be located, hence possesses marked advantages 60 over the traps now employed in the art to which this invention relates, and since it dispenses with all projections, partitions and recesses, it offers minimum resistance to the flushing, scouring flow of the waste-water.

65 Having thus described my invention, what

I claim and desire to secure by Letters Patent is:—

1. A sanitary self-sealing and self-cleaning trap for bath tubs, comprising a single casting of cast iron formed with a large 70 main body portion, a threaded integral inlet at one side of the body portion, a threaded integral outlet at the opposite side of the body portion with its inner end connected in alinement with the bottom of said body and its outer end extending outward and upward at an angle with respect to said body portion and terminating on the same horizontal plane with the inlet and diametrically opposite said inlet. 75

2. A sanitary self-sealing and self-cleaning trap for bath-tubs, comprising a single casting of cast iron formed with a large cylindrical main body having a flat top and bottom portion, a threaded integral inlet at 80 one side of the body portion, a threaded integral outlet at the opposite side of the body portion with its inner end connected in alinement with the bottom of said body and its outer end extending outward and upward at an angle with respect to said body portion and terminating on the same horizontal plane with the inlet and diametrically opposite said inlet. 85

3. A sanitary self-sealing and self-cleaning trap for bath tubs, comprising a single casting of cast iron formed with a large main body portion of uniform diameter, a threaded integral inlet at one side of the 100 body portion, a threaded integral outlet at the opposite side of the body portion with its inner end connected in alinement with the bottom of said body and its outer end extending outward and upward 105 at an angle with respect to said body portion and terminating on the same horizontal plane with the inlet and diametrically opposite said inlet, an integral strengthening rib connecting the outlet to the body portion. 95

4. A sanitary self-sealing and self-cleaning trap for bath tubs, comprising a single casting of galvanized cast iron formed with a large cylindrical main body portion of uniform diameter and having a flat top and bottom, a threaded integral inlet at one side 115 of the body portion, a threaded integral outlet positioned diametrically opposite of said inlet with its inner end connected in alinement with the flat bottom of the body portion and its outer end extending outward 120 and upward at an angle with respect to said body portion, and terminating on the same horizontal plane in alinement with the inlet. 125

5. A sanitary self-sealing and self-clean-

ing trap for bath tubs, comprising a single casting of galvanized cast iron formed with a drum-shaped body portion of uniform diameter from top to bottom, a threaded integral inlet at one side of the body portion, a threaded integral outlet formed diametrically opposite said inlet with its inner end connected in alignment with the bottom of the body portion and its outer end ex-

tending outward and upward at an angle 10 with respect to the body portion terminating on the same horizontal plane in alignment with said inlet, and a screw-threaded nickel-plated cover provided with an annular rim extending beyond the outer surface 15 of the said body portion.

HARRY C. ODENKIRK.
